UNITED STATES PATENT OFFICE.

GEORGE W. BURTON, OF BORDENTOWN, NEW JERSEY.

SAW-VISE.

SPECIFICATION forming part of Letters Patent No. 296,128, dated April 1, 1884.

Application filed November 13, 1883. (No model.)

To all whom it may concern:

Be it known that I, GEORGE W. BURTON, a citizen of the United States of America, residing at Bordentown, in the county of Burlington and State of New Jersey, have invented certain new and useful Improvements in Saw-Vises, of which the following is a specification, reference being had therein to the accompanying drawings.

10 My invention relates to an improved saw-vise for holding saws rigidly in position for sharpening and setting the saw-teeth; and it consists in the longitudinal jaws A, pivoted at either end to the adjustable feet B and B', which are hinged together in pairs, each pair comprising a jaw and bench clamp actuated by a headed thumb-screw, C, and in the combination and arrangement of the parts, substantially as hereinafter more fully shown and 20 described.

In the drawings, Figure 1 is a side elevation. Fig. 2 is a plan view, showing the feet folded down; and Figs. 3 and 4 are detail views.

25 In the construction of my saw-vise I employ two coincident longitudinal bars, A', comprising the jaws A, which are provided with a recess, a, at each end thereof to provide space for the saw-handle. The bars A' have pivoted thereto at b b the adjustable feet B and B', having the right-angular projecting arms C', the bars being provided at each end with coincident recesses e e to form shoulders, against which in practice the arms C' abut, in order 30 to thus support in a horizontal position jaws

A, which in practice hold the saw inclosed in a horizontal plane and longitudinally. The adjustable feet B and B' are hinged together, the foot B having cast integral therewith and projecting therefrom the hinge-bar b², which 40 is pivoted by means of pin b³ in socket b⁴ of foot B'. The adjustable feet B and B' are formed to project slightly beyond the hinge-bar b², where they are curved and widened to jointly form clamps D, composed of the jaws 45 E and E'.

Through eyes F, provided in jaws B, project the headed thumb-screws C, thus forming a bench-clamp at either end of the saw-vise for securing the device in an upright position, as 50 shown in Fig. 1; and it will be observed that in proportion, as by means of the thumb-screws, the saw-vise is tightened on the bench, the arms C' tighten the grasp of the vise on the saw.

Having thus described my invention, what I claim is—

A saw-vise consisting of jaws A, having recesses e, adjustable feet B and B', hinged together, and each having a projecting arm, C', 60 headed thumb-screws C, and clamps D, to clamp the device to a bench and to close the jaws, substantially as shown and described.

In testimony whereof I affix my signature in presence of two witnesses.

GEORGE W. BURTON.
